(57) **CLAIM**

The ornamental design for a minivan to campervan conversion kit, as shown.

DESCRIPTION

FIG. 1 is a rear perspective view of a minivan to campervan conversion kit;

FIG. 2 is a front perspective view of the minivan to campervan conversion kit of FIG. 1;

FIG. 3 is a left side perspective view of the minivan to campervan conversion kit of FIG. 1;

FIG. 4 is a right side perspective view of the minivan to campervan conversion kit of FIG. 1;

FIG. 5 is a top perspective view of the minivan to campervan conversion kit of FIG. 1;

FIG. 6 is a bottom perspective view of the minivan to campervan conversion kit of FIG. 1;

FIG. 7 is a front left-side perspective view of the minivan to campervan conversion kit of FIG. 1;

FIG. 8 is a front left-side perspective view of the minivan to campervan conversion kit of FIG. 1, with doors and drawers in open configuration;

FIG. 9 is an exploded perspective view of the minivan to campervan conversion kit being unassembled, showing a kitchen module on the right and an unassembled storage module on the left; and,

FIG. 10 is rear perspective view of the minivan to campervan conversion kit of FIG. 1, assembled and installed in a minivan to convert it from a standard minivan to a camper minivan.

The broken lines illustrate portions of the minivan to campervan conversion kit that form no part of the claimed design.

1 Claim, 10 Drawing Sheets
